SANDER

Forist Harris, Merced, Calif., assignor to Brunswick-Balke-Collender Company, Chicago, Ill.,
a corporation of Delaware

Application November 30, 1946, Serial No. 713,278

9 Claims. (Cl. 51—175)

1

This invention relates to, and it is an object to provide, an improved portable floor sanding machine, especially a machine adapted for finish-sanding floors, bowling alleys, or the like.

Another object of the invention is to provide a floor sanding machine wherein the floor engaging sandpaper is reciprocated in the direction of travel to avoid the marking of the floor which results from the use of rotary type sanding machines; the sandpaper lying flat on the floor at all times during operation of the machine, and the entire weight of the latter being imposed on said paper. In this manner a very accurate and fine appearing finish may be applied to the floor.

It is also an object of this invention to provide a floor sanding machine, as above, wherein the floor engaging sandpaper, in addition to being reciprocated in the direction of travel, is simultaneously oscillated in a horizontal plane so as to accomplish a very effective sanding action.

An additional object of the invention is to provide a floor sanding machine which includes a main frame having an electric motor mounted thereon, longitudinally spaced, flat sandpaper blocks below the main frame in horizontal alignment, the blocks being secured to the frame for limited longitudinal reciprocation and supporting said frame, and means between the motor and blocks operative to so reciprocate the latter.

A further object of the invention is to provide a practical sander, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the floor sanding machine in position for use.

Fig. 2 is a rear end view of the machine in position for use.

Fig. 3 is a diagrammatic view of the eccentric assembly.

Fig. 4 is a fragmentary plan view of one of the throw-over latches illustrating the manner of its engagement with the adjacent leg of the bail-type handle.

Referring now more particularly to the characters of reference on the drawings, the improved floor sanding machine comprises a rigid main frame, indicated generally at 1; said main frame being of inverted U-shape and extending transversely of the direction of travel.

2

A pair of mounting yokes 2 of inverted U-shape are attached at the top, by bolts 3, in transversely spaced relation, and at right angles to the corresponding part of the main frame 1. The mounting yokes 2 are attached to the main frame 1 in symmetrical relation, i. e. projecting ahead and to the rear of said main frame equal distances.

Below the assembly of the main frame 1 and mounting yokes 2 the machine includes a pair of flat, horizontal sandpaper blocks 4 which are rectangular in plan but elongated transversely of the machine. The sandpaper blocks 4 are aligned lengthwise of the direction of travel and are spaced apart so that one block is disposed below the forward pair of legs of the mounting yokes 2, while the other block is disposed below the rearward pair of said legs. Such pairs of legs approach closely to the corresponding blocks substantially centrally between the forward and rearward edges of the same, and are there connected by bolts 5 with cross bars 6 secured between upstanding flanges 7 on top of said blocks 4. Resilient or cushion washers 8 are interposed between the bolts 5 and the parts connected thereby.

The mounting yokes 2 are of spring steel so that the sandpaper blocks are capable of limited reciprocating movement horizontally in the direction of travel.

An electric motor 9 is mounted in connection with, and depends from, the top of the rigid main frame 1, and drives a cross shaft 10, journaled in said frame, through the medium of an endless belt and pulley unit 11.

Adjacent each end of the cross shaft 10, and in alignment with corresponding legs of the mounting yokes 2, said shaft is fitted with a pair of eccentric units, the units of each pair being indicated at 12 and 13, and each is attached to a connecting rod 14. The connecting rods 14 of each pair of eccentric units extend in opposite directions through adjacent legs of the mounting yokes 2, being secured to said legs by nuts 15 threaded on said rods on opposite sides of the legs. Resilient or cushion washers 16 are disposed on the rods 14 between the nuts 15 and connected legs of the yokes 2.

The bottom surface of each sandpaper block 4 is roughened, as at 17, and a sheet of sandpaper 18 lies flat against said surface transversely of the blocks 4, turning upwardly at the ends of the latter, as shown in Fig. 1. The roughened bottom surface of the sandpaper block tends to prevent displacement of the paper

from its proper position. The upturned ends of the sandpaper sheets 18 are secured to upstanding end flanges 19 on the blocks by means of heavy-duty clips 20. These clips maintain the sandpaper sheets under proper tension and against escape from the blocks 4 when the machine is in operation.

When the machine is in operation it is disposed with both sandpaper blocks bearing flat against the floor. Thereafter, upon actuation of the electric motor 9, with resultant rotation of the cross shaft 10, the eccentric units 12 reciprocate the connecting rods 14, together with said sandpaper blocks. This reciprocation of the sandpaper blocks is through a relatively short stroke, but at substantial speed; the cushion washers 8 and 16 tending to absorb any abrupt action and minimizing vibration. The reciprocation of the sandpaper blocks 4 is of course possible, as previously explained, for the reason that the mounting yokes 2 are of spring steel.

Most efficient operation of the machine is accomplished when the eccentric units 12 and 13 of each pair are opposed or set 180° apart, with the corresponding eccentrics of the opposite end pairs (i. e. eccentrics 12—12, and 13—13) set to run 90° apart.

With this arrangement of the eccentrics the sandpaper blocks not only reciprocate, in opposition, lengthwise of the direction of travel, but they also simultaneously oscillate in a horizontal plane, thus accomplishing a rapid, effective, and accurate sanding action. Further, as the reciprocation is in the direction of travel, or lengthwise of the grain of the floor, as in a bowling alley, no undesirable floor marking occurs, as is the case with rotary type sanding machines.

Also, the machine is quite efficient for the reason that the entire weight thereof bears on the sandpaper blocks 4 when such machine is in operation.

Dust removal from the machine is accomplished as follows:

Hoods 21 are mounted along the outer transverse edges of the sandpaper blocks 4, and another hood 22 spans between adjacent transverse edges of said blocks, the hood 22 being flexible to permit of relative movement between the blocks as the machine operates. Suction hoses 23 lead from the above described hoods upwardly to the intake of a suction fan unit 24 mounted in the main frame 1. The suction fan unit 24 is driven from the cross shaft 10 by an endless belt and pulley unit 25. The discharge 26 of the suction fan unit 24 delivers to a dust carry-off hose 27 which leads to a suitable bag, or other dust receptacle.

The machine is guided, when in operation, by a swinging or bail-type handle 28 pivoted, as at 29, to opposite ends of the rigid main frame 1. For transport of the machine the handle 28 may be locked in a vertical position by throw-over latches 30 hingedly mounted on top of the main frame 1, and being forked, as at 31, to straddle the adjacent leg of the handle 28 when it is in said upright position.

To facilitate movement of the machine, when not in use, along a floor a pair of rigid arms 32 are fixed in connection with opposite ends of the rigid main frame 1 and extend rearwardly to a termination beyond the rearmost sanding block. At their outer ends the arms 32 are fitted

with rollers 33. To so move the machine the bail-type handle 28 is locked up in its vertical position, and the machine then rocked rearwardly by said handle until the rollers 33 come into floor engagement and the sandpaper blocks 4 rise free of the floor. Thereafter the machine can be readily rolled along the floor from place to place.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as described by the appended claims.

Having thus described the invention, the following is claimed as new and useful, and upon which Letters Patent are desired:

1. A floor sanding machine comprising a main frame, a mounting yoke of inverted U-shape secured to the main frame with the yoke legs spaced apart in the direction of travel, a sandpaper block disposed below each yoke leg, means securing each block to the corresponding yoke leg, said legs being of spring metal whereby the blocks are mounted for limited reciprocating motion in said direction, an electric motor on the main frame, and means driven by the motor operative to horizontally reciprocate the blocks; said means including a motor-driven cross shaft, eccentric units on the shaft corresponding to the yoke legs, and connecting rods between the eccentric units and said corresponding legs.

2. A floor sanding machine comprising a main frame, a mounting yoke of inverted U-shape secured to the main frame with the yoke legs

spaced apart in the direction of travel, a sandpaper block disposed below each yoke leg, means securing each block to the corresponding yoke leg, said legs being of spring metal whereby the blocks are mounted for limited reciprocating motion in said direction, an electric motor on the main frame, and means driven by the motor operative to horizontally reciprocate the blocks; said means including a motor-driven cross shaft, eccentric units on the shaft corresponding to the yoke legs, and connecting rods between the eccentric units and said corresponding legs, there being cushion means interposed between each connecting rod and corresponding leg.

3. A floor sanding machine comprising a main frame, a mounting yoke of inverted U-shape secured to the main frame with the yoke legs spaced apart in the direction of travel, a sandpaper block disposed below each yoke leg, means securing each block to the corresponding yoke

leg, said legs being of spring metal whereby the blocks are mounted for limited reciprocating motion in said direction, an electric motor on the main frame, and means driven by the motor operative to horizontally reciprocate the blocks; said means including a motor-driven cross shaft, eccentric units on the shaft corresponding to the yoke legs, and connecting rods between the eccentric units and said corresponding legs, there being cushion means interposed between each connecting rod and corresponding leg, and between each leg and the corresponding block.

4. A floor sanding machine comprising a main frame of inverted U-shape disposed transversely of the direction of travel, a pair of inverted U-shape mounting yokes secured to the top of

the main frame with the legs of each yoke spaced lengthwise of said direction, a flat, horizontal sandpaper block disposed below the front and rear pairs of the yoke legs, said legs being of spring metal, means securing each block to the corresponding pair of legs, an electric motor mounted on the main frame, and motor driven means operative to horizontally reciprocate the blocks in said direction.

5. A floor sanding machine comprising a main frame of inverted U-shape disposed transversely of the direction of travel, a pair of inverted U-shape mounting yokes secured to the top of the main frame with the legs of each yoke spaced lengthwise of said direction, a flat, horizontal sandpaper block disposed below the front and rear pairs of the yoke legs, said legs being of spring metal, means securing each block to the corresponding pair of legs, an electric motor mounted on the main frame, and motor driven means operative to horizontally reciprocate the blocks in said direction; said motor-driven means comprising a cross shaft journaled in connection with and extending between the legs of the main frame, driving connections between the motor and shaft, an eccentric unit on the shaft corresponding to each yoke leg, and a connecting rod between each of the eccentric units and the corresponding yoke leg.

6. A floor sanding machine comprising a main frame of inverted U-shape disposed transversely of the direction of travel, a pair of inverted U-shape mounting yokes secured to the top of the main frame with the legs of each yoke spaced lengthwise of said direction, a flat, horizontal sandpaper block disposed below the front and rear pairs of the yoke legs, said legs being of spring metal, means securing each block to the corresponding pair of legs, an electric motor mounted on the main frame, and motor driven means operative to horizontally reciprocate the blocks in said direction; said motor-driven means comprising a cross shaft journaled in connection with and extending between the legs of the main frame, driving connections between the motor and shaft, an eccentric unit on the shaft corresponding to each yoke leg, and a connecting rod between each of the eccentric units and the corresponding yoke leg, the pair of eccentric units corresponding to the legs of each block being fixed on the shaft with one of said pair leading the other whereby to cause horizontal oscillation of such block simultaneously with reciprocation thereof.

7. A floor sanding machine comprising a main frame of inverted U-shape disposed transversely of the direction of travel, a pair of inverted

U-shape mounting yokes secured to the top of the main frame with the legs of each yoke spaced lengthwise of said direction, a flat, horizontal sandpaper block disposed below the front and rear pairs of the yoke legs, said legs being of spring metal, means securing said block to the corresponding pair of legs, an electric motor mounted on the main frame, and motor driven means operative to horizontally reciprocate the blocks in said direction; there being suction hoods adjacent the edges of the blocks, a suction fan unit on the main frame driven by the motor, suction conduits between the hoods and fan unit, and a discharge conduit leading from said fan unit.

10 8. In a sanding machine the combination of: a main frame, a motor mounted on the main frame, an abrading block, a hanger connected to the block at each end thereof and to the frame and mounting the block for simultaneous reciprocating and oscillating movement in a horizontal plane relative to the frame, and a separate connection between the motor and each of the hangers and operative to impart a differential reciprocating movement thereto.

20 9. In a sanding machine the combination of: a main frame, a motor mounted on the main frame, an abrading block, means supporting the block from the frame, a driving member connected to the block at each end thereof, and connections between the motor and driving members, such connections being effective to impart a differential reciprocating movement to said driving members upon operation of the motor.
